UNITED STATES PATENT OFFICE.

ARTHUR R. SMITH, OF CLEVELAND, OHIO; IDA SMITH, ADMINISTRATRIX OF SAID ARTHUR R. SMITH, DECEASED, ASSIGNOR OF ONE-HALF TO JAMES S. SMITH AND ONE-HALF TO IDA SMITH.

SMOKE PRODUCER.

Application filed March 11, 1924. Serial No. 698,469.

The invention relates to apparatus for, and process of, treating smoke-producing material and its discharge into the atmosphere for the purpose of producing clouds, screens, 5 streams, etc.

The invention is concerned more particularly to discharge of smoke-producing material or smoke from heavier-than-air craft in skywriting, but it pertains also to treatment of smoke material in other places and 10 for other purposes.

It is an object of the invention to provide efficient means easily controlled by the operator, and methods easily and efficiently carried out for treatment of smoke material and 15 its discharge into the atmosphere either as smoke or as a substance or mixture of substances that will produce smoke on contact with the atmosphere.

Another object of the invention is to provide means whereby heat derived from an engine, such an internal-combustion propelling-engine of an aircraft, is employed to bring smoke-producing material to such temperature as will convert it into smoke either 20 in the apparatus or on discharge into the atmosphere.

Further, the invention provides other means for igniting smoke material or causing 25 its ignition.

When considered in connection with the description herein, the characteristics of the invention are apparent from the accompanying drawings, forming part hereof, wherein 30 adaptations of the invention are disclosed, for purposes of illustration.

Although the disclosures herein exemplify what now are considered to be preferable embodiments of the invention, it is to be understood that it is not the intention to be limited 35 necessarily thereto in interpretation of the claims, as modifications and adaptations within the limits of the claims can be made without departing from the nature of the invention.

Like reference-characters refer to corresponding parts in the views of the drawings, of which—

Fig. 1 is a view of an apparatus for discharge of smoke material in powdered or similar form;

Fig. 2 is a view of another form of apparatus for that purpose;

Fig. 3 is a view of an apparatus wherein air

is heated for application to smoke material; 55

Fig. 4 is a detail view thereof;

Fig. 5 is a view in elevation of another apparatus wherein heated air is employed;

Fig. 5^a is a plan view thereof;

Fig. 6 is a view of an apparatus that involves electrical ignition of smoke material;

Fig. 7 is a view of an arrangement for ignition of smoke material by burners;

Fig. 8 is a view of an apparatus in which discharge of smoke material is effected by 65 fluid under controlled pressure; and

Fig. 9 is a view of an apparatus that includes means for controlling the temperature of smoke material by a temperature-controlled circulating fluid. 70

In the views of the drawings in which those parts appear, D designates an internal-combustion engine, such as, for example, the propelling-engine of an aircraft, E an exhaust-conduit of the engine, and SM a tank, 75 casing, or other container of smoke material.

Referring to Figs. 1 and 2, the container SM has a hopper bottom 11, from which leads a discharge-port 12 fitted with a semi-spherical screen 13 arranged for passage therethrough of smoke material in comminuted, granular, or similar form. Stirrer or agitator members 14 are arranged to cooperate with the screen to cause passage of the material therethrough. These members are mounted 85 on a shaft 15, which is rotated by an engine-driven shaft 16 through the instrumentality of a clutch or other power-transmission device 17. The device 17 is controlled by a swingably-mounted arm 18, which may be 90 swung by a member 19 extending to a place within reach of the operator.

In the form of apparatus exemplified by Fig. 1, the port 12 communicates with a discharge-conduit 20, through which a current 95 of gaseous fluid is caused to flow, and the conduit has a discharge end 21 turned to direct the stream of emission therefrom into the stream of hot fluid discharged from the end of the exhaust-conduit E, the end 21 being outside of and near the discharge end of the conduit E. Fluid may be caused to flow through the conduit 20 toward its discharge end in any suitable manner. When the apparatus is installed in an aircraft or other vehicle, the conduit may be fitted at its front end with an air-scoop 22. If desired, a bypass 23 may lead from the conduit 20 to the 100 105 110

upper portion of the smoke-material container, as shown in Fig. 1, in order to equalize pressure in the container.

When the stirrer members 14 are inactive, 5 no appreciable amount of smoke material is discharged through the screen 13 into the conduit 20. When the operator wishes to effect such discharge, the parts of the clutch 17 are thrown into engagement and the shaft 15 10 caused to rotate. The smoke material then entering the conduit 20 is taken up by the fluid current therein and discharged into the stream of hot fluid emitted from the exhaust conduit. On contact with the hot exhaust 15 fluid, the smoke material ignites and evolves or produces smoke. The discharge of smoke material is under control of the operator at all times by means of the clutch, the fluid current in the conduit 20 is sufficiently rapid to insure 20 almost instant delivery of smoke material to and its ignition by the hot exhaust current after the material is discharged from the conduit, and production of smoke is as instantly discontinued on cessation of operation of the 25 stirrer members.

Among the materials that can be used satisfactorily in an apparatus of this sort is red phosphorus in powdered or similar form. It 30 ignites in the air when heated to 500 degrees F. or thereabout, and sufficient heat for that purpose is afforded by the exhaust of an internal-combustion engine when the material is brought into contact with the exhaust current at or near its place of discharge into the 35 atmosphere.

The apparatus is capable of operating not only with smoke material in dry condition, but also in moist condition as when mixed with a suitable liquid into a plastic or semi- 40 plastic state, in melted condition, and in other forms constituting masses that will not pass in undesirable quantities through the screen when the stirrer members are inactive.

In some circumstances, red phosphorus and 45 other smoke material suitable for use in the apparatus may be liable to preignite when brought into the presence of air in the discharge-conduit. In order to avoid such pre- 50 ignition, and also to produce ignition at the desired place, apparatus of the form disclosed by Fig. 2 is provided. Therein the discharge-conduit 20, instead of being arranged to have 55 an air current maintained therein, has non-inflammable fluid, such as carbon-dioxide gas, for example, delivered thereto from a tank 24 by a pipe 25.

The fluid passing from the tank may be heated in any suitable manner. A convenient and effective means of heating is by disposing 60 a portion of the pipe 25 as a heater in proximity to the exhaust-conduit, as by passing it therearound as a coil 26.

When heated inert or non-inflammable fluid is applied to smoke material in the course of 65 its passage toward discharge, the temperature

of the mixture may be such as of itself to cause ignition of smoke material of some characteristics upon its release into the atmosphere. In such case, it is not necessary to bring the discharged stream containing smoke material into the presence of the exhaust or other ignition instrumentality.

However, when the smoke material is of such character as to require it to be brought, for ignition, into the presence of heat on discharge, whether it is in a current of air as in the case of an apparatus such as exemplified by Fig. 1 or in a heated or unheated non-inflammable current as with an apparatus of a type exemplified by Fig. 2, instead of being discharged into the exhaust stream in a manner such as disclosed by Fig. 1, ignition may be effected as disclosed by Fig. 2. In that arrangement, the conduit 20 and the exhaust-conduit discharge into an open-ended casing 80 27 comprehending an ignition-chamber and having an air-scoop 28 at its front end, the conduit 20 delivering to the chamber in advance of the exhaust-conduit.

When the rearwardly-flowing smoke material delivered to the chamber contacts with the hot exhaust delivered thereto, ignition and smoke production occur, and a trail of smoke subsists to the rear of the ignition-chamber. Delivery of smoke material to the 95 conduit 20 and thus production of smoke are controlled in the same manner as in the form exemplified by Fig. 1 or in any suitable manner.

The invention also provides means for employing heat, otherwise than by bringing smoke material directly into the presence of engine exhaust, for ignition of smoke material, and also for its treatment.

Referring to Figs. 3 and 4, the exhaust-conduit E leads from the side of the rear portion of an elongated casing 29, and exhaust-pipes E' deliver from the engine-cylinders into the casing. The casing is closed at its front and rear ends by walls 30 (see Fig. 4), 110 and these walls support a plurality of pipes, tubes, or other suitable conduits 31, which extend from end to end of the casing and are open at their front and rear ends. Air may be caused to flow through the tubes 31 and be 115 heated by the exhaust in the casing in any suitable manner. When the apparatus is installed in a vehicle, such as an aircraft, for example, the front end faces the direction of the vehicle's motion and air flow through the 120 tubes occurs while the vehicle is in motion. In order to increase the air flow, the front end of the casing may be equipped with an air-scoop 32, if desired. The heated air discharges into a conduit 33 connected with the 125 rear end of the casing 29.

Air thus heated may be employed in the operation of a smoke apparatus in any of several ways.

As shown by Fig. 3, the conduit 33 may dis-

charge directly into the atmosphere, and smoke material may be delivered to the discharged current of hot air by a pipe 20^a and ignited in a manner similar to that pertaining to the apparatus exemplified by Fig. 1 or by Fig. 2. The smoke material may be supplied to pipe 20^a by gravity from a container SM and its flow controlled by a valve 34, as shown by Fig. 3; it may be controlled by a stirrer and caused to move to the discharge as shown by Figs. 1 and 2; or the smoke material may be caused to move to the discharge end of the conduit by fluid-pressure means such as disclosed by Fig. 8 hereinafter more particularly referred to or by my copending application Ser. No. 654,887, filed July 31, 1923.

Air heated in an apparatus such as exemplified by Figs. 3 and 4 not only may be employed for direct ignition of smoke material, but it also may be used for treatment of such material. For example, referring to the apparatus exemplified by my application herein before mentioned, instead of directing engine exhaust through pipe 9 into the casing 4, a pipe leading from the air-heater, such as conduit 33, may be substituted for pipe 9. In such case, hot air flow into the casing 4 may be controlled in any suitable manner, as, for example, by means similar to that employed for control of exhaust flow through pipe 9 of said application and more particularly referred to hereinafter with reference to the apparatus exemplified by Fig. 5.

In the type of apparatus disclosed by Fig. 5, instead of employing a plurality of air-conduits, the elongated casing 29 is open at both ends, its front end has an air-scoop 32, and its rear end is contracted as shown at 35. The exhaust-pipes E' extend into the casing, and they are joined to and deliver into the exhaust-conduit E, which extends outwardly through the rear portion of the casing as a discharge-outlet E''. A turnable elbow 36 is arranged to have its intake end brought opposite and close to the discharge end 35 of the casing 29, and its movement is controlled by a member 37 extending to a place where it can be reached conveniently by the operator. The elbow is mounted and turnable on the end portion of a conduit 33^a, which communicates with the place in the apparatus to which it is desired to deliver air for ignition, heating, or cooling purposes. The character of the air, so far as concerns temperature, delivered to the conduit is controlled by movement of the elbow to alter the relative position of its intake end with respect to the discharge end of casing 29, it being apparent that the maximum amount of hot air is received from the casing when the intake end of the elbow is in registry therewith, and a less amount of hot air and more air from the atmosphere are taken in as the elbow is moved from that position. Accordingly, by moving the intake end out of the stream of discharge

from the casing, air at approximately atmospheric temperature may be delivered into the conduit 33^a and used for cooling purposes. Consequently, when smoke material nearly reaches a temperature that is dangerous or otherwise disadvantageous in the apparatus, cooling fluid may be applied at once thereto.

An apparatus for electric-spark ignition of smoke material is exemplified by Fig. 6, wherein SM designates any suitable smoke-material container, 20^a a discharge-conduit leading therefrom, and controlled, if desired, by a valve 34, and 38 designates electrodes, such as those of a spark-plug, for example, positioned outside of and near the discharge end of the conduit and arranged to produce a spark in the discharge stream. Conductors 39 for the electrodes are connected with any suitable source of electricity, such as a magneto 40, for example, and a switch 41 controls the spark circuit. Movement of smoke material through the conduit 20^a may be caused and controlled in any suitable manner, as, for example, by means such as described herein with reference to other exemplifications of the invention.

The invention also provides for flame ignition of smoke material at or near its place of discharge into the atmosphere, as disclosed by Fig. 7. In that figure, one or more burners 42 are positioned near the discharge end of conduit 20^a to direct flame into the stream of discharge containing smoke material emitted from that conduit, whereby the smoke material is ignited. The burners are supplied with inflammable fluid by a pipe 43, controlled by a valve 44, connected with a tank 45.

Some of the materials used for production of smoke are corrosive and are liable to injure valve structures, and they are liable to clog valve ports and passages and the like. It is desirable, therefore, to afford clear and unobstructed passages for movement of smoke material. With these factors, among others, in view, the invention provides an apparatus such as exemplified by Fig. 8.

That apparatus includes a shaft 15 rotated by an engine-driven shaft 16 through the instrumentality of a clutch or other power-transmission device 17 controlled by a lever 18, as in the case of the apparatus exemplified by Figs. 1 and 2. The shaft 15 is arranged to drive a pump 46, which delivers liquid from a storage-tank 47 through pipes 48 to a smoke-material container SM and from which smoke material in fluent condition is dischargeable through a pipe 20^a. A relief-valve 49 is located in a pipe 48 between the pump and the container SM, and a bypass 50 leads therefrom to the storage-tank.

Discharge of smoke material from the receptacle SM is under the direct control of the operator through the instrumentality of the clutch. When the clutch is thrown in and the pump operated, any suitable fluid,

such as water, for example, is pumped from the storage-tank into the upper portion of the container SM and the smoke material thereby is forced outwardly through the discharge-pipe 20^a; and, immediately upon throwing out the clutch and stoppage of the pump, discharge of smoke material ceases. The relief-valve is set so that, when the pressure of fluid in the pipe leading to the container is sufficient to maintain discharge of smoke material during operation of the pump, some of the fluid may be returned to the storage-tank through the by-pass and excess pressure avoided.

15 While any suitable fluid may be employed in the apparatus exemplified by Fig. 8, it is particularly adapted for employment of water or other liquid. The apparatus may be used in place of the air-pressure arrangement for causing fluid pressure in the receptacle 19 of my co-pending application hereinbefore mentioned, or in apparatus of the type exemplified by Fig. 9 hereinafter described, or in other smoke apparatus wherein controlled pressure is desirable for effecting, or contributing to, discharge of smoke material.

20 Fig. 9 exemplifies an arrangement for controlling the temperature in a container, and it is adapted for use with a jacketed container such as disclosed by my copending application hereinbefore referred to and to other apparatus in which temperature controlling or modifying fluid is applied to casings, pipes, and other containers of smoke material.

25 The apparatus exemplified by Fig. 9 includes a container SM arranged to hold smoke material and having a jacket 51 affording passages through which fluid can be moved, a pump 46 operated by an engine-driven shaft 15 arranged to cause circulation of fluid (preferably liquid such as water) through conduits 52, 53 and 54 and a heat transfer device 55 to which pipes 53 and 54 are connected.

30 The device 55 may be of a radiator type, it has in its top an opening, closed by a removable cap 56 through which liquid may be introduced into the circulating system, and it has tubes or other passage-containing members 57 extending therethrough and through the fluid therein and open at their ends. An intake member or scoop 58 at the front of the device is arranged to receive fluid and direct it through the members 57.

35 The exhaust-conduit E has mounted thereon a swingable terminal 36^a arranged to be swung by a control member 37 to bring its discharge end to and from position opposite to the intake 58. Temperature of the circulating fluid applied to the container SM

is controlled by adjustment of the terminal 36^a. When it is desired to maintain the circulating fluid at high temperature, the terminal is positioned with its end in registry with the intake, when practically all of the exhaust will be discharged into the device 55. When the terminal is adjusted to other positions, less exhaust and more air will be received by the device, it being assumed that the apparatus is installed in a vehicle and that the intake faces toward the direction in which the vehicle moves. If it is desired to bring the circulating fluid to, and maintain it at, the minimum temperature for the purpose of cooling smoke material, the terminal is adjusted to such position entirely out of registry with the intake as will result in discharge of all of the exhaust into the atmosphere and air only passes through the device.

Having thus described my invention, what I claim as new, and desire to secure by Letters Patent, is—

1. In a smoke apparatus, the combination of an exhaust-conduit of an internal-combustion engine, a discharge-conduit, a container of non-inflammable fluid, a delivery-conduit communicating with said container and discharge-conduit and arranged to be heated by said exhaust-conduit, and a smoke-material container having a discharge-passage communicating with said discharge-conduit.

2. In a smoke apparatus, the combination of an exhaust-conduit of an internal-combustion engine, a discharge-conduit arranged to discharge into the emission of said exhaust conduit, a container of non-inflammable fluid, a delivery-conduit communicating with said container and discharge-conduit, and a smoke-material container having a discharge-passage communicating with said discharge-conduit.

3. In a smoke apparatus, the combination of an exhaust-conduit of an internal-combustion engine, a discharge-conduit, a container of non-inflammable fluid, a delivery-conduit communicating with said container and discharge-conduit and arranged to be heated by said exhaust-conduit, a smoke-material container having a discharge-passage communicating with said discharge-conduit, and ignition means for smoke material supplied to said discharge-conduit.

4. In a smoke apparatus, a discharge conduit, a smoke-material container having a discharge-passage communicating with said conduit, a by-pass extending from said conduit to said container, a device arranged to cause discharge of material through said passage, and means whereby said device is operated and rendered inoperative at will.

In testimony whereof, I affix my signature.

ARTHUR R. SMITH.
